AMPLIFYING SYSTEM

Vernon D. Landon, East Pittsburgh, Pa., assignor
to Westinghouse Electric & Manufacturing
Company, a corporation of Pennsylvania

Application July 22, 1927. Serial No. 207,619

7 Claims. (Cl. 179—171)

My invention relates to amplifying systems, and it has particular relation to systems designed for the amplification of high-frequency alternating currents.

5 Radio signals, when received from far distant points, generally have an amplitude that is too small to be at once rectified and applied to an indicating device. It is, therefore, customary to precede the rectifier or demodulator by an amplifying system of some sort, that of the usual type comprising a plurality of three-electrode thermionic tubes connected in cascade by coupling devices, such as transformers. For the most efficient amplification at radio-frequencies, 10 it is customary to so tune the coupling transformers between the adjacent thermionic tubes that they are substantially resonant to the frequency to be received, according to the teaching of the Alexanderson Patent No. 1,173,079, employing, for this purpose, a plurality of variable condensers, or variable inductors.

In accordance with the present tendency of the art toward the simplification of radio apparatus, separate controlling devices for the variable tuning elements have been replaced by uni-control devices arranged to simultaneously alter the electrical characteristics of the said tuning elements. In view, however, of the practically insurmountable difficulties encountered in making 25 identically similar inductors and capacitors on a commercial scale, the simultaneous tuning of a plurality of amplification stages to exact resonance is not capable of economical commercial attainment, the best results obtained hitherto being 30 only approximations.

It is, accordingly, one object of my invention to provide a multi-stage high-frequency amplifier that shall be capable of being precisely tuned by a single tuning condenser.

40 Another object of my invention is to provide a high-frequency amplifier that, when properly adjusted, does not tend to spontaneously oscillate.

Another object of my invention is to provide, in a multi-stage amplifier of the type first above 45 referred to, means whereby the selectivity thereof shall be equally as good as that obtained through the use of a plurality of tuned stages.

Another object of my invention is to provide, in a multi-stage amplifier, means whereby regeneration is obtained at the frequency to which the single tuning means is momentarily adjusted, with no tendency toward regeneration of incoming signals at differing frequencies.

Another object of my invention is to provide an 55 amplifying system that very materially reduces

the effect of static interference with received signals.

Another and more specific object of my invention is to provide an efficient amplifying system wherein other than the usual three-electrode tubes are employed.

I attain these objects by making use of a plurality of thermionic devices of the type wherein a grid is utilized to control the flow of current between an anode and an electron-emissive cathode, and a second grid is interposed between the control grid and the cathode in order to reduce the so-called space-charge effect. By proper circuit connections, which will later be explained in detail, the effect of a single tuned 70 circuit is reflected back into the preceding stages of a multi-stage amplifier employing tubes of the type referred to, whereby the effect of a plurality of tuned circuits is simulated without actually employing more than the single tuned stage 75 mentioned previously.

Among the features that I consider characteristic of my invention are those set forth with particularity in the appended claims. The invention itself, however, both as to its organization 80 and its method of operation, together with further objects and advantages thereof, will best be understood by reference to the following description, taken in connection with the accompanying drawing, in which:

85 Figure 1 is a diagrammatic view illustrating the principle underlying my invention.

Fig. 2 is a diagrammatic view of a multi-stage amplifying system comprising a preferred embodiment of my invention.

90 Referring specifically to Fig. 1, a thermionic device 1 comprising a filament 2, a space-charge grid 3, a control grid 4 and an anode 5, is provided with a source of filament potential 6. The positive pole of a potential source 7 is connected 95 to the anode by a conductor 8, and an intermediate point on said source is connected to the space-charge grid 3 through an inductor 10 shunted by a tuning condenser 11.

95 A source 12 of alternating current is connected 100 between the control grid 4 and the filament 2, a resistor 13 and a condenser 14 being interposed in the conductor leading from the source 12 to the grid 4. A resistor 15, a condenser 16 and a grid leak 17 are also connected between 105 the control grid and the filament, in shunt to the source 12. A conductor 18 extends from the space-charge grid 3 to one plate of a small condenser 20, the other plate of which is connected to the input circuit by a conductor 21.

85

110

The space-charge grid and the filament are connected to succeeding amplifier stages by means of conductors 22 and 23, respectively. The succeeding stages may comprise additional amplifiers or may comprise a detector and audio-frequency amplifying devices.

The thermionic device illustrated is of the type described in a patent to Van der Bijl, No. 1,479,779, wherein is shown an additional electrode, known as the "space-charge grid", interposed between the usual control-grid and the filament, in order to neutralize, to some extent, the space charge which surrounds the filament and is generally conceded to comprise a vast number of free electrons. When a constant positive potential is impressed on the space-charge grid, with respect to the cathode, the impedance between the anode and the cathode is materially lowered, and it has also been observed that the current flowing to the space-charge grid varies oppositely to the current flowing in the anode circuit when a variable potential is impressed upon the control grid. That is to say, as the current to the anode increases, the current to the space-charge grid decreases, and vice versa.

By reason for this phenomenon, since the voltage at the plate, provided the plate load is resistive in character, is 180° out of phase with the voltage of the control grid, it is clear that the voltage of the space-charge grid will be in phase with the exciting voltage when its external load is resistive.

By suitably tuning an output circuit associated with the space-charge grid to the frequency impressed upon the control grid, such output circuit assumes the characteristics of a pure resistance. If the inductor and condenser which comprise the said output circuit were entirely free from losses, the resistance of the tuned circuit to the resonant frequency would be infinite.

The more nearly the characteristics of the output circuit associated with the space-charge grid approach the characteristics of a pure resistance, the more nearly will the voltage of the space-charge grid come into synchronism with the voltage on the control grid. It is, therefore, apparent that, if the tuned output circuit 10-11 is replaced by a pure resistance, the conditions of a tuned circuit will be simulated.

If the alternating potential source 12 supplies to the control grid of the thermionic device 1 a potential varying at a definite frequency, and if the output circuit 10-11 is tuned to this frequency, the voltage on the space-charge grid will be in synchronism with that voltage being impressed on the said control grid. The impressed voltage causes a current to flow both in the resistor 15 and in the condenser 16 connected in shunt thereto. By suitably adjusting the capacity of the condenser 20 connected between the space-charge grid and the control grid, with respect to the voltage developed at the space-charge grid, it is possible to cause a current to flow in the said condenser equal in amount and in direction to the current flowing in the condenser 16 by reason of the input excitation. Under such circumstances, the reactance of the input condenser is neutralized, and the input circuit, therefore, displays resistive characteristics only.

This system of capacity neutralization may be applied to amplifying devices in order to increase the tuning range thereof. The stray capacity associated with the input circuits of the various thermionic tubes embodied in an amplifier sys-

tem places a definite limit below which the system cannot be tuned. Such capacities may be cancelled to any desired degree by adjusting the feed-back from the space-charge grid to the control grid, thus increasing the wave-length range at the short-wave end of the scale. The long-wave end of the scale will be only slightly affected, since a much larger capacity is being employed for tuning and only a very small percentage of it will be cancelled.

Various other uses of capacity-cancellation will suggest themselves and one use in particular which I consider extremely valuable and important is in connection with a multi-stage amplifier.

A preferred embodiment of my invention that is shown in Fig. 2 comprises a plurality of four-electrode thermionic devices 31, 32 and 33, with which are associated untuned coupling networks comprising resistors 34 and condensers 35 analogous to the resistor 15 and the condenser 16 shown in Fig. 1. Each of the four-electrode thermionic devices is, in addition, provided with a capacity-neutralization condenser 36 equivalent to the condenser 20 shown in Fig. 1. The resistor 34 and the condenser 35 at the left of the thermionic device 31 may be included in an antenna-ground circuit, as illustrated.

The thermionic device 33 is further provided with a tunable output circuit equivalent to the circuit comprising the inductor 10 and the variable condenser 11, which output circuit is coupled to the input electrodes of a detector tube 37. The tunable output circuit preferably takes the form of a band-pass filter 38 capable of being tuned to offer substantially the same impedance to a plurality of frequency bands, each band being wide enough to accommodate the side bands associated with any incoming frequency in the range of frequencies which the set is intended to receive. In its simplest form, the band-pass filter 38 comprises merely an inductor having a tuning condenser connected in shunt thereto, although it may comprise a plurality of elements arranged according to the well-known teachings of Campbell and Pupin.

The anodes of the three four-electrode thermionic devices are connected, by means of a conductor 41, to a point on a voltage source 42 of slightly more positive potential than a point 125 thereon to which the space-charge grids of the same devices are connected by means of a conductor 43.

The plate of the detector tube 37 is connected to the voltage source 42 through the primary 44 of an audio-frequency transformer 45, the secondary 46 of which may either be connected directly to a sound-producing device, such as a telephone or a loud speaker 47, or may be connected to succeeding audio-frequency amplifier stages.

The filaments of all of the thermionic devices are supplied from a single source 48, and a source 50 of grid-biasing potential may be utilized to supply a negative bias to the control grids of all of the devices, if such bias is found necessary and desirable.

The space-charge grid of each tube is connected to the control grid of the succeeding tube through a small grid condenser 51. The antenna resistor 34 associated with the thermionic device 31 supplies a path for the application of grid-bias potential to the said device, while the bias potential for the devices 32, 33 and 37 is supplied through resistors 52, 53 and 54, respectively.

When in operation, the band-pass filter 38 is

tuned to the frequency of an incoming signal and, consequently, the load in the output circuit of the device 33 becomes purely resistive at such frequency. As explained in connection with the 5 condenser 20 of Fig. 1, the condenser 36 of Fig. 2, connected between the control and space-charge grids of the thermionic device 33, is adjusted to that value which causes neutralization of the reactance of the condenser 35 shunting the coupling resistor 34, and the load, therefore, which the said resistor causes in the space-charge grid circuit of the thermionic device 32 also becomes purely resistive in character.

By a repetition of the same sequence of events, 15 the reactance of the condenser 35 in the network between thermionic devices 31 and 32 is neutralized, as is also the reactance of the condenser 35 associated with the resistor 34 in the antenna-ground circuit.

20 The amplifier system, accordingly, exhibits the same characteristics that it would exhibit if all of the resistor-capacity networks were replaced by inductor-capacity networks, in the manner shown in the patent to Alexanderson 1,173,079, which patent discloses the principle of tuned 25 radio-frequency amplification.

A certain small amount of energy at frequencies different from the frequency to which the 30 band-pass filter, or tuned output circuit of the thermionic device 33, is tuned may lead through the amplifier, regardless of the retroactive effect 35 of the said tuning. However, this interference, or leakage, may be controlled in any desired degree by increasing the capacities of the three feed-back condensers 36 and the three shunting condensers 35.

If desired, the system may be so arranged that 40 a sufficient amount of regeneration is present to increase the selectivity. This may be accomplished by increasing the capacity of the feed-back condensers or by increasing the voltage 45 across the tuned output circuit.

It is thus apparent that I have devised an 50 amplifying system wherein a plurality of un-tuned coupling networks are utilized, the said networks being so associated with other elements that they may be caused to exhibit the characteristics of tuned networks. Inasmuch as the simplest embodiment of my invention necessitates only a single tuned circuit, I have thus eliminated 55 the necessity of closely matching inductors and condensers in order to attain uni-control.

Although I have illustrated and described only 60 a single embodiment of my invention, the underlying principles thereof are capable of application to a large number of radio receiving and transmitting devices. It is also feasible to apply my invention to the repeater systems used in wired telegraphy and telephony and in wired

radio, and to the amplifiers utilized in connection with the reception of signals over submarine cables.

It is my intention, therefore, that no limitations 80 shall be placed on my invention, except such as may be necessitated by the prior art and are embodied in the appended claims.

I claim as my invention:

1. In combination, a plurality of thermionic devices arranged in cascade, coupling networks comprising resistive and reactive elements between certain of said devices, and means for neutralizing the reactive components of said networks at any desired frequency. 85

2. In combination, a plurality of thermionic devices arranged in cascade, coupling networks comprising capacitive elements between certain of said devices, means simulating an electrical filter between other of said devices, and means whereby an alteration of the characteristics of said filter 90 may be caused to also alter the capacitive reactance of at least one of said networks.

3. In combination, a plurality of thermionic devices of the four-electrode type comprising a control grid and a space-charge grid, coupling networks including capacitive elements between certain of said devices, and means whereby variations 100 in potential of said space-charge grids are utilized to neutralize the reactance of said capacitive elements. 105

4. The combination of a non-resonant circuit including resistive and capacitive elements, a four-electrode thermionic device comprising a control grid and a space-charge grid, a tunable output circuit associated with said space-charge grid, 110 and means for so associating said output circuit with said non-resonant circuit that the latter is caused to exhibit certain of the characteristics of resonance at the frequency to which said output circuit is tuned. 115

5. A system for selecting electrical oscillations of a given frequency from oscillations differing therefrom in frequency, comprising a plurality of thermionic amplifying devices connected in cascade by non-resonant circuits comprising mainly 120 resistive and capacitive elements, and means for giving to said non-resonant circuits the substantially selectivity of resonant circuits.

6. A series of four-electrode vacuum-tube amplifiers connected in succession, the outer grid of each tube being connected to the inner grid of the neighboring tube by way of a coupling condenser. 125

7. A series of four-electrode vacuum-tube amplifiers connected in succession, the outer grid of each tube being connected to the inner grid 130 of the neighboring tube by way of a coupling condenser, and the anode-cathode circuits of all said tubes being in parallel.
